(57) **CLAIM**

The ornamental design for a rolling self-watering garden bed, as shown and described.

DESCRIPTION

FIG. 1 is a first perspective view of a rolling self-watering garden bed showing a new design;

FIG. 2 is another perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a partially enlarged view showing the area 9 in FIG. 2.

The broken lines in the drawings illustrate the portions of the rolling self-watering garden bed, which form no part of the claimed design.

The long dash-short dash broken lines indicate cutoff boundaries for enlarged detail portion views and form no part of the claimed design.
